UNITED STATES PATENT OFFICE.

DANIEL G. ELSEN, OF BROOKLYN, NEW YORK.

METHOD OF EMBOSSED PRINTING.

Application filed April 3, 1922. Serial No. 549,120.

To all whom it may concern:

Be it known that I, DANIEL G. ELSEN, a citizen of the United States, and a resident of the city of New York, borough of Brooklyn, in the county of Kings and State of New York, have invented a new and improved Method of Embossed Printing, of which the following is a full, clear, and exact description.

10 This invention relates to the art of printing and has more particular reference to a method of embossed printing on fabric or other flexible materials.

15 Broadly the invention contemplates a method of embossed printing on a flexible material whereby the embossing or raising of the characters and the imposing of the ink thereon is accomplished simultaneously.

20 As a further object the invention contemplates a method of embossed printing on a flexible material in which the embossing is accomplished by means of a heated embossing element and in which a dry ink is employed which liquefies under the action of 25 heat and is released and deposited by the action of said heated embossing element.

25 The invention contemplates more specifically a method of embossed printing for garment labels in order to closely simulate 30 woven or embroidered labels whereby to reduce the cost of production of labels of this character.

35 With the above recited and other objects in view, the invention resides in the method set forth in the following specification, pointed out in the appended claims and illustrated in the accompanying drawings, it being understood that variations and modifications which properly fall within the scope of the 40 appended claims may be resorted to when found expedient.

In the drawing—

45 Figure 1 is a fragmentary sectional view illustrating the apparatus employed for carrying out the method prior to the printing and embossing operation.

Fig. 2 is a similar view illustrating the operation.

50 Figure 3 is a face view of the printing die or type.

Fig. 4 is a view of the completed article or label.

55 Referring to the drawings by characters of reference, 10 designates a base plate or block upon which a compressible sheet or element 11, such as paper or the like coated

on its upper face with dry ink 12, is arranged. The fabric or other material 13 constituting the body of the label or other article is arranged face downward on the 60 dry coating. A die block 14 having an embossed or raised character 15 on its under side is superposed with respect to the fabric or other material and is adapted to be brought into forcible engagement and contact with the upper rear face of said fabric or material.

The method consists essentially in heating the die 14 and the embossed or raised character 15 thereon to a predetermined degree 70 and then forcing the same into contact with the rear face of the fabric or material to emboss or raise that portion of the material with which the character 15 coacts. The heated embossed surface releases a chemical 75 in the dry ink and liquefies the same to cause it to adhere to the embossed character formed on the under and outer face of the fabric or material. The compressible sheet or strip 11 permits and compensates for the 80 impression formed by the raised character.

I claim:

1. A method of embossed printing consisting in presenting the material to be embossed and printed, to an ink adapted to liquefy under the action of heat, and subjecting said material to the pressure of a heated embossing element.

2. A method of embossed printing consisting in disposing the material to be embossed and printed on a yieldably supported dry ink adapted to liquefy under the action of heat, and subjecting said material to the pressure of a heated embossing element.

3. A method of embossed printing consisting in disposing the material to be embossed and printed on a yieldably supported dry ink adapted to liquefy under the action of heat, and subjecting said material simultaneously to the action of heat and an embossing element.

4. A method of embossed printing consisting in presenting the face of the material to be embossed and printed to a yieldably supported dry ink adapted to liquefy 105 in the presence of heat, and subjecting said material to the pressure of the raised or embossed characters of a heated or embossed element.

5. A method of embossing and printing a 110 flexible material to simulate embroidered or woven characters consisting in simulta-

neously raising the characters on the front face of the material by forcing the embossed characters of a heated die against the rear face thereof and presenting said characters simultaneously on a dry ink adapted to liquefy under the action of heat.

6. The herein described method of embossed printing consisting in imposing the material to be embossed and printed face 10 downward on a rigidly supported compressible element having on its upper face a coating of drying ink adapted to liquefy under

the action of heat and compressing against the uppermost face of the material a heated die having raised characters on its under 15 face, whereby to cause said characters to raise similar characters on the under face of the material for effecting through the medium of the heated contacting surfaces a liquefaction and release of the dry ink from 20 the compressible element and the transferring and adherence of the same to the raised characters on the face of the material.

DANIEL G. ELSEN.
